(57) **CLAIM**

The ornamental design for a housing for an electrical connector, as shown and described.

DESCRIPTION

FIG. 1 is a rear elevational view of a housing for an electrical connector showing my new design;

FIG. 2 is a right side view thereof;

FIG. 3 is a front elevational view thereof;

FIG. 4 is a left side view thereof;

FIG. 5 is a bottom plan view thereof;

FIG. 6 is a top plan view thereof;

FIG. 7 is a top, front and side perspective view; and,

FIG. 8 is a top, side, and rear perspective view.

The broken lines in FIGS. 1, 5 and 8 are included for the purpose of illustrating portions of the “housing for an electrical connector” that forms no part of the claimed design.
